CONTAINER-DISPENSERS

Ferdinand Eduard Martin Haafkens, Utrecht, Netherlands, assignor to Unicura N. V., Oss, Netherlands, a company of the Netherlands

Application January 29, 1953, Serial No. 333,923

Claims priority, application Netherlands February 5, 1952

6 Claims. (Cl. 128—216)

This invention relates to container-dispensers comprising an ampoule of thermoplastic material having secured thereto a tube which is not in communication with the interior of the ampoule. The tube may be a hypodermic needle to provide a container-dispenser in the form of a hypodermic syringe, or it may have rounded ends and, if desired, be soft and flexible to provide, for example, a container-dispenser in the form of an eye dropper. In use, communication is established between the tube and the interior of the ampoule, and the ampoule contents are then dispensed through the tube by squeezing the ampoule.

It will be evident that movement of the tube during application—whether the container-dispenser is in the form of a hypodermic syringe or in the form of an eye dropper—is objectionable. Such movement is caused by squeezing of the ampoule and is particularly severe if considerable pressure is required or if the ampoule can only be emptied by being kneaded.

It is an object of the present invention to provide improvements in container-dispensers which facilitate the emptying of the ampoule.

According to the present invention there is provided a container-dispenser comprising a substantially tubular ampoule of thermoplastic material having a substantially rigid neck and a tube secured in the said neck, which tube is not in communication with the interior of the ampoule, the ampoule being flattened and the two major opposite sides formed by said flattening gradually approaching one another as they approach the neck.

The ampoule has preferably an oval cross section, in which case the minor axis is gradually reduced as it approaches the neck. The two major opposite sides of the ampoule are preferably provided with flats.

It is also preferred that one of the major sides of the ampoule is less rigid than the other.

Preferred embodiments of container-dispensers according to the present invention will now be described with reference to the accompanying drawing in which:

Fig. 1 shows a plan view of a container-dispenser in the form of a hypodermic syringe,

Fig. 2 shows an elevation of the container-dispenser shown in Fig. 1,

Fig. 3 shows a cross-section of the neck of the container-dispenser shown in Figs. 1 and 2,

Fig. 4 shows a cross-section on the line IV—IV of the container-dispenser shown in Fig. 1,

Fig. 5 shows a cross-sectional plan view of an alternative form of a container-dispenser in the form of a hypodermic syringe,

Fig. 6 shows an elevation partly in section of the container-dispenser shown in Fig. 5, and

Fig. 7 shows a cross-section of a portion of a container-dispenser in the form of an eye dropper.

Like reference numerals will be used to designate like parts.

Referring to Figs. 1—4, the container-dispenser has an ampoule 1 of thermoplastic material, for example, poly-

2

ethylene. The ampoule has a substantially rigid neck 2 provided with a duct 3. The tube 4, in the form of a hypodermic needle, is secured in the duct 3 by a close fit. The duct 3 is separated from the interior of the ampoule by a separator in the form of a thin membrane 5 integral with the ampoule. The diameter of the duct 3 adjacent to the membrane 5 is reduced to a smaller cross-section 6 to prevent the needle piercing the membrane on insertion. This reduction of the cross-section creates a shoulder 7 which acts as a stop for the needle. The two opposite sides of the ampoule which approach one another as they approach the neck are provided with flats 8 and 9 respectively. One of the major sides of the ampoule, see Fig. 4, is thinner and, consequently, less rigid than the other major side. This reduction in rigidity of one of the major sides facilitates further the emptying of the ampoule without substantially weakening the container-dispenser.

A stiff pointed wire 10 situated in the bore of the needle 4 is provided for piercing the membrane 5. The wire 10 is provided with a disc 12 which protects the end of the needle against shock. The neck and tube is covered by a protective cover 11 of thermoplastic material which fits onto the outside of the neck 2.

The container-dispenser is filled through the bottom of the ampoule 1 which is open prior to filling. The bottom of the ampoule is then heat-sealed by a seam 13 at right angles to the longitudinal axis of the container-dispenser and parallel to the flats 8 and 9, any excess liquid being forced out of the ampoule during sealing. The length of the major axis of the ampoule, that is the axis parallel to the seam 13 is substantially constant throughout the length of the ampoule.

The container-dispenser shown in Figs. 5 and 6 differs from that shown in Figs. 1—3 by the shape of the ampoule and by the means of securing the tube 4 in the substantially rigid neck. As before, the seam 13 is at right angles to the longitudinal axis of the container-dispenser, but the length of the major axis is not constant.

The tube 4, which is in the form of a hypodermic needle, is secured in a needle holder 14. The needle may be inserted into the needle holder 14 with a close fit or the holder may be moulded round the needle. In order to lock the needle holder 14 in the neck, the outer end of the duct 3 is provided with a narrow part 15. The needle holder 14 is rounded at 16 to enable the narrow part 15 to be deformed to permit insertion of the holder. The shoulder 7 now serves as a stop for the needle holder.

The embodiment shown in Fig. 7, in which the tube is relatively soft and flexible is intended, for example, for use as an eye dropper. The tube 4, which may be of nylon, is secured in the duct 3 of the neck 2. The tube may be coloured to indicate the contents of the ampoule. In this embodiment the protective cover 12 is so shaped that it closes the end of the tube 4. Thus even when the membrane 5 has been pierced with the stiff wire, which in the embodiment having this type of cover is provided separately, the cover also acts as a closure for the tube.

I claim:

1. A container-dispenser comprising in combination a substantially tubular ampoule of thermoplastic material having a substantially rigid neck and a tube secured in the said neck, which tube is not in communication with the interior of the ampoule, the ampoule being provided with two major opposite sides which gradually approach one another as they approach the neck, one of the said major sides of the ampoule being less rigid than the other.

2. A container-dispenser comprising in combination a substantially tubular ampoule of thermoplastic material having a substantially rigid neck and a hypodermic needle secured in the said neck, which hypodermic needle is not in communication with the interior of the ampoule, the

ampoule being provided with two major opposite sides which gradually approach one another as they approach the neck, one of the said major sides being less rigid than the other.

3. A container-dispenser comprising in combination a substantially tubular ampoule of thermoplastic material having a substantially rigid neck and a hypodermic needle secured in the said neck, which hypodermic needle is not in communication with the interior of the ampoule, the ampoule being provided with two major flat sides which approach one another as they approach the neck, one of the major sides being less rigid than the other.

4. A container-dispenser comprising in combination a substantially tubular ampoule of thermoplastic material having a substantially rigid neck and a hypodermic needle secured in the said neck, which hypodermic needle is not in communication with the interior of the ampoule, the cross-section of the ampoule being oval, said ampoule having two major opposite sides gradually approaching one another as they approach the neck, one of the major sides being less rigid than the other.

5. A container-dispenser comprising in combination a substantially tubular ampoule of thermoplastic material having a substantially rigid neck, a hypodermic needle secured in the said neck, a puncturable membrane integral with the ampoule to prevent communication between the interior of the ampoule and the hypodermic needle, and a stiff wire situated in the said hypodermic needle for piercing the membrane, the ampoule being provided with two major opposite sides which gradually

approach one another as they approach the neck, one of the said major sides being less rigid than the other.

6. A container-dispenser comprising in combination a substantially tubular ampoule of thermoplastic material having a substantially rigid neck, a hypodermic needle secured in the said neck, a puncturable separator arranged to prevent communication between the interior of the ampoule and the hypodermic needle, and a stiff wire situated in the said hypodermic needle for piercing the separator, the ampoule being provided with two major opposite sides which gradually approach one another as they approach the neck, one of the said major sides being less rigid than the other.
